ERNEST CANTELO WHITE, OF NEW YORK, N. Y., ASSIGNOR TO ELECTRIC OUTLET COMPANY, INC., OF NEW YORK, N. Y., A CORPORATION OF NEW YORK.

ELECTRICAL CONNECTING AND SUPPORTING DEVICE.

1,363,942.

Specification of Letters Patent.

Patented Dec. 28, 1920.

Application filed January 10, 1920. Serial No. 350,689.

To all whom it may concern:

Be it known that I, ERNEST CANTELO WHITE, a citizen of the United States, residing in the borough of the Bronx of the city 5 of New York, in the State of New York, have invented certain new and useful Improvements in Electrical Connecting and Supporting Devices, of which the following is a specification, reference being had to 10 the accompanying drawing, forming a part hereof.

In a copending application filed by the present application on January 10, 1920, Serial Number 350,688, there is shown and 15 described an electrical connecting and supporting device with reference primarily to its application to the attachment of a fixture to a ceiling. In said application the principle on which the improved support is 20 based is claimed broadly. The present invention relates to an electrical connecting and supporting device in which the same principle, broadly, is employed, but in which the embodiment is somewhat different. In 25 accordance with the invention two conductor arms carrying a pendant support for an electrical attachment extend into curved grooves in a receptacle but the weight of the fixture instead of being borne wholly along 30 the edges of the grooves as described in said copending application is transmitted to the receptacle partly along the edges of the grooves and partly through the engagement of the conductor arms beyond the grooves 35 with the receptacle.

Reference is now to be had to the accompanying drawing for a detailed description of one construction by which the present objects of the invention are realized, in which 40 drawing—

Figure 1 is a view in vertical section through a flush receptacle showing the application of the improved electrical connecting and supporting devices thereto.

Fig. 2 is a view in horizontal section taken through the flush receptacle shown in Fig. 1.

Fig. 3 is a view in transverse section taken through the insulating blocks on which are carried the conductor arms.

Fig. 4 is a view in horizontal section taken through the blocks shown in Fig. 3.

As pointed out in said copending application while electrical connecting and supporting devices of the general character covered by that application may be em-

ployed with surfaces inclined at any angle to the horizontal and with electrical attachments of any form, the immediate problem is concerned with the hanging of lighting fixtures from a ceiling in such manner as to afford universality of application thereof through the improved support and ready interchangeability of fixtures. Accordingly, the embodiment incorporating the features of the present invention has been shown and will be described in connection with the support of a lighting fixture which may be carried on some such pendant support as is indicated at *a*, from an outlet box embedded in the ceiling, such as is indicated at *b*. The outlet box is shown as having secured to its lower edge a ceiling plate *c*, as by means of screws *d*, which plate may have a central opening, indicated at *c'*, which is closed by means of an insulating face plate *e* supported on the plate *c*. In the illustrated embodiment the insulating plate *e* is shown as resting on the plate *c* and secured against dislodgment by means of screws *e'*. On the insulating plate *e* is supported an insulating block *f* chambered, as at *f'*, *f''*, to receive terminals *g*, *g'* which are connected to the leads of any available source of current supply. Through-bolts *f''* may be passed through the block *f* and the plate *e* for the purpose of securing the block to the plate and the plate *e* may be recessed, as at *e''*, to receive the heads *f''*, of these bolts in such manner as to preserve the sightliness of the exposed surface of the plate. The block *f* forms a receptacle with the plate *e*. The terminals *g*, *g'* may be formed of opposed spring plates for a reason which will later appear.

In the insulating plate *e* are formed curved grooves *e''*, *e'''* adapted to receive curved conductor arms *h*, *i*. As illustrated, the grooves *e''*, *e'''* are curved in opposite directions and spaced apart a distance determined by the distance between the arms *h*, *i*, so that these arms when inserted into the respective grooves extend into the chambers *f'*, *f''*, respectively, in opposite directions. The groove *e''* and the arm *h* are curved on arcs struck about a center indicated at *k*, and the groove *e'''* and arm *i* are curved along arcs struck about a center indicated at *l*. The arms *h*, *i* beyond their respective grooves *e''*, *e'''* merge into straightened sections *h'*, *i'*, respectively, which, when the arms are prop-

erly positioned, present a bearing surface, preferably of somewhat substantial area to the reverse face of the insulating plate *e*.

The lower ends of the arms *h*, *i* are secured by any suitable means, such as through-studs *h*², *i*², to semi-cylindrical segmental insulating blocks *h*³, *i*³, respectively. The segments *h*³, *i*³ are recessed along their diametrical meeting faces, as at *h*⁴, *i*⁴, respectively, to receive the respective conductor arms *h*, *i*, and their securing devices *h*², *i*² with ample clearance to prevent short circuiting at this point. The studs *h*², *i*² may have threaded on their inner ends binding nuts *h*⁵, *i*⁵, respectively, to afford a convenient means of connecting the studs with the respective wires *m*, *m'* of the electrical attachment. It is to be understood that the conductor arms *h*, *i* may be attached to their respective insulating blocks *h*³, *i*³ by means other than those described herein and that the electrical connections between such conductors and the wires *m*, *m'* may be of other forms and independent of the attaching means for such arms. The segmental blocks *h*³, *i*³ when placed together with their diametrical meeting faces in contact constitute a true cylinder, and are threaded exteriorly to receive a locking ring *n* whereby the blocks are held in this relationship and the arms *h*, *i* locked in place in the grooves *e*², *e*³ as will presently appear.

The particular improvements with which this application is concerned will now be pointed out in detail in connection with the method of assembling the parts described and their respective functions when in use. It is contemplated that each electrical attachment or fixture carried on the pendant support *a* will have attached to its support a locking ring, such as *n*, for universality of application to the improved connecting and supporting devices. Such an attachment or fixture will have its wires *m*, *m'* connected electrically to the respective conductors *h*, *i*, the ring at this time being removed from the blocks *h*³, *i*³. One of the conductor arms *h* will then be manipulated so as to pass it upwardly through the groove *e*² in the plate *e* until the segment *h*³ bears against the underface of the plate *e*, the block during this assembling being so manipulated as to permit the arm *h* to conform to the curvature of the groove *e*² and finally reach a position of rest within the chamber *f'* in which it is in electrical contact with the terminal *g* and has its end *h'* resting on the reverse face of the plate. The other arm *i* will then be passed upwardly in a similar manner through its groove *e*³ until it comes to rest in a corresponding position within the chamber *f'*, at which time it will be in electrical connection with the terminal *g'* and its end *i'* will rest against the inner face of the plate *e*.

The center *k* of the arcs on which the groove *e*² and curved portion of the conductor arm *h* are described rests on or without the periphery of the segment *h*³ so as to permit the assembling operation described. In the same manner the center *l* for the arcs on which the groove *e*³ and curved portion of the conductor arm *i* are laid out will lie on or outside of the periphery of the segmental block *i*³. When the parts are thus assembled the locking ring *n* is threaded on to the blocks until its upper edge is brought into snug engagement with the face of the plate *e*. The sides of the arms *h*, *i* nearest to their respective blocks *h*³, *i*³, bear on the respective grooves *e*², *e*³. In this condition there is a turning movement impressed on the conductor arm *h* by the weight of the electrical attachment which turning moment about the respective bearing surface tends to withdraw the arm *h* through the groove *e*² about the center *k* and an equal and opposite turning moment is impressed on the conductor arm *i* tending to withdraw it from its groove *e*³ about the center *l*. These turning moments when the blocks *h*³, *i*³ are locked together are equal and opposite and so equalized. The weight of the fixture is then borne by the plate *e* partially through the horizontal and vertical components of force transmitted to the plate along the edges of the slots *e*², *e*³, and partially by vertical lines of force transmitted to the plate at the points of contact between the straight ends *h'*, *i'* of the conductor arms *h*, *i* and the reverse face of the plate. By thus affording points of support for the conductor arms at other points on the plate than along the edges of the slots *e*², *e*³, the weight of the fixture is more evenly distributed through the body of the plate and the lateral stresses which would otherwise be imposed thereon are reduced.

Changes in the forms of the electrical connections herein shown and described and in the details of the mechanical connections and in the precise forms and relation of the conductor arms and their associated parts may be made without departing from the scope of the invention provided that the weight of the fixture is carried by elements which correspond in function to the elements illustrated and which have somewhat the same operative relation.

I claim as my invention:

1. An electrical connecting and supporting device including a ceiling receptacle formed with an entrance opening and provided with a terminal, and a plug member including fixture supporting means, a conducting and supporting member to engage the terminal, and insulating means between the fixture supporting means and said conducting member, said receptacle and terminal including a horizontal bearing surface

- within the receptacle for the side of the conducting and supporting member nearest to the plug member, said receptacle and plug member also including coöperating means 5 for resisting the turning moment of the conducting and supporting member about the said bearing surface by the weight of a fixture on the fixture supporting means.
2. An electrical connecting and supporting device including a ceiling receptacle formed with entrance openings and provided with terminals, and a plug member including fixture supporting means, two bent conducting and supporting members extending in opposite directions and engaging the respective terminals, and insulating means between the fixture supporting means and said conducting members, said receptacle and terminals including horizontal bearing surfaces 15 for said supporting and conducting members.
3. An electrical connecting and supporting device including a ceiling receptacle formed with entrance openings and provided with terminals, and a plug member including fixture supporting means, two bent conducting and supporting members extending in opposite directions to engage the respective terminals and having flat bearing portions beyond the bent portions, respectively, 20 on the sides nearest to the plug member, and insulating means between the fixture supporting means and said conducting members, said receptacle and terminals including horizontal bearing surfaces for the said flat portions of the conducting and supporting members.
4. A ceiling receptacle for an electrical connecting and supporting device formed 25 with entrance openings, for two conducting and supporting members of a fixture supporting plug member of the device extending in different directions, and provided with terminals in the same vertical planes with the entrance openings, respectively, to be engaged by the conducting and supporting members, said receptacle and terminals including horizontal bearing surfaces within the receptacle for the sides of the conducting and supporting members nearest to the plug 45 member.
5. A ceiling receptacle for an electrical connecting and supporting device formed with entrance openings for two bent conducting and supporting members of a fixture 55 supporting plug member of the device extending in opposite directions, and provided with terminals in the same vertical planes with the entrance openings, respectively, to be engaged by the conducting and supporting members, said receptacle and terminals including horizontal bearing surfaces on which the conducting and supporting members rest.
6. A plug for a ceiling electrical connecting and supporting device including fixture supporting means, two separable conducting and supporting members inclined in different directions to enter a receptacle of the device and engage terminals therein, said members having horizontal supporting surfaces adjacent their ends, and insulating means between the fixture supporting means and said conducting members, said insulating means and fixture supporting means including 60 means to hold said supporting members against relative movement.

This specification signed this 19th day of December, A. D. 1919.

ERNEST CANTELO WHITE.
